UNITED STATES PATENT OFFICE

ERICH WIPPERMANN, OF HAGEN-DELSTERN, GERMANY

PISTON INTERNAL COMBUSTION ENGINE WITH CYLINDER STARS ARRANGED ONE BEHIND THE OTHER IN A COMMON FRAME

Application filed January 8, 1931, Serial No. 507,379, and in Germany August 22, 1928.

This invention relates to piston internal combustion engines with cylinder stars arranged one behind the other in a common frame.

In the known constructions of such engines the cylinder frame is stationary so that the upwardly directed cylinders have too little lubrication and the lower cylinders too ample lubrication which leads to trouble as regards ignition and to soiling of the pistons and valves.

This invention overcomes this objection in that a driving device is provided by means of which the cylinder frame can be slowly rotated whilst the engine is running. Besides obtaining a uniform lubrication, a uniform distribution of the wear of the entire engine is also ensured and at the same time the fitting and supplying of water cooling for the cylinders is rendered possible. Owing to the slow speed of rotation of the cylinder frame, it is possible to control the engine accurately.

The liquid fuel may preferably be supplied by a distributor rotating with the cylinder frame and to which the individual branch pipes leading to the carburetors are connected.

Further a separate cooling device with a pump may be provided for each row of cylinders, the suction pipe of each pump taking cooling water from a common tank when the row of cylinders is in a certain position during the rotation of the frame, whereas their pressure pipes lead to a common collecting vessel rotating with the frame and from which a hot water pump leads off the water.

An embodiment of the invention illustrates by way of example a four-stroke cycle piston internal combustion engine with six cylinder stars arranged one behind the other in a common frame, in which

Fig. 1 is a front elevation partly in section.

Fig. 2 is a side elevation also partly in section.

The individual cylinders are designated by 25 and the common carrying frame by 26.

The liquid or gaseous fuel is supplied from the fuel tank 1 through supply pipe 2 and an annular distribution chamber 3 to the carbure-

retors of the individual cylinders 25. On the covers of the individual cylinders admission valves 4, exhaust valves 5 and also suction and exhaust pipes 21 and 22 respectively are arranged. A sparking plug 24 is also fitted on the cover of each cylinder. The connection of the pistons 27 running in the cylinders 25 to the crank shaft 30 is effected so that the piston rods 31 are connected to the crank shaft 30 by means of eccentric discs 32 keyed thereon.

The operation of the admission valves 4 and also of the exhaust valves 5 is effected from cam shafts 35 arranged on the cylinder frame 26, by means of valve levers 33 and valve rods 34 actuated from the crank shaft by means of toothed wheel drive 19.

Magneton 6 are provided for the ignition and supply their current to the sparking plugs 24.

The water cooling works intermittently which is necessitated by the construction of the engine, but in no way impairs the reliable working thereof. A separate centrifugal pump 36 is provided for the water cooling of each row of cylinders. During the slow revolution of the cylinder frame 26 the extended dipper pipes 8 dip alternately into a tank 13 arranged at the bottom, which is provided with a supply pipe 14 and a discharge pipe 15. The result is, that the jackets 7 of the cylinders are supplied for a certain time, about 10 seconds, with cooling water through the feed pipes 9, whereas the hot water flows off through the discharge pipes 10 into the tank 11 which is mounted on the shaft 30 and also rotates slowly with the cylinder frame 26. The water is forced from the collecting tank 11 into the cooler by means of a pump 12 and after cooling is returned to the tank 13 through the pipe 14.

The drive of the separate centrifugal pumps 36 is effected by electric motors 37 supplied with current from a dynamo 16. The dynamo 16 is driven from the crank shaft 30 and the current produced is transmitted to insulated collector bars 18 by means of a stationary sliding contact, the collector bars being fixed on the engine shaft and the cur-

rent is supplied from these bars to the motors 37.

As shown on the left side of Fig. 1, a hollow axle arm 28 is flanged onto the cylinder frame 26. This arm can turn in an outer bearing 29 and serves at the same time for the passage of the fuel feed pipe 2.

The rotation of the cylinder frame 26 is effected by a worm gear 38 with self-braking pitch. Thus it is possible to cut out entirely the slow rotation of the cylinder frame, so that the working parts, especially the sparking plugs, can be accurately controlled.

The exhaust gases are led off through the exhaust pipes 22 arranged in star shape into a silencer preferably fitted behind the engine shaft.

I claim:

20 A piston internal combustion engine, comprising in combination a plurality of cylinder stars arranged one behind the other, a common frame carrying said cylinder stars, a driving mechanism adapted to slowly rotate said cylinder frame whilst the engine is running, and means to ensure uniform lubrication and wear of the running surfaces, said driving mechanism being arranged and adapted to vary the speed of rotation of the cylinder frame, and to be disconnected therefrom.

In testimony whereof I affix my signature.
ERICH WIPPERMANN.
